INVENTOR
Stevens,

UNITED STATES PATENT OFFICE.

CLARENCE E. STEVENS, OF WEST HAVEN, CONNECTICUT.

LIGHT-SHIELD.

1,316,654.

Specification of Letters Patent. Patented Sept. 23, 1919.

Application filed June 1, 1918. Serial No. 237,758.

To all whom it may concern:

Be it known that I, CLARENCE E. STEVENS, a citizen of the United States, residing at West Haven, in the county of New Haven and State of Connecticut, have invented certain new and useful Improvements in Light-Shields, of which the following is a specification.

This invention relates to illumination, and more especially to dimmers; and the object of the same is to produce a device for cutting off rays, whether the same are produced by a lighted lamp or by the phantom light resulting from a beam shining into the reflector.

It is well known, especially to railroad men, that by day or by night the phantom light produced by a beam shining against a highly polished reflector can hardly be distinguished from the rays emanating from the lighted lamp itself. The light shining may come from a distant point, and perhaps it might even be sunlight. The purpose of my present invention is the production of a shield which will positively cut off the rays of light from the lamp itself if the same be lighted or will positively prevent the entrance of the foreign beam from another source and which by reflection in the reflector of the lamp would give the appearance of a light.

This object is accomplished by the shield structure described below and shown in the drawings, wherein:

35 Figure 1 is an elevation,

Figs. 2 and 3 vertical sections on the line 2—2 and 3—3 of Fig. 1 looking in the direction of the arrows respectively opposite said lines in this view, and

40 Fig. 4 is a horizontal section on the line 4—4 of Fig. 1.

This device as a whole comprises a base 1 which may well be pivotally mounted at 2 on the bottom B of a lamp box X which is shown only in outline in Fig. 2 of the present drawings, and may have a slot 3 cut around its pivot and movable over a bolt 4 so that adjustment of the base and the parts carried thereby can be effected. Upstanding from the sides of the base are standards 5 to which at 6 are pivoted arms 7 carrying a shield 8 which may well be slightly dished or concavo-convex as shown, and which should be blackened inside and outside so that it can have no reflective properties. This entire structure is to be mounted with

in the lamp box X between its lamp L and reflector R. I might say, however, that while the lamp herein is a bulb L disposed directly above the base the character of the lamp or lantern and its means of illumination are not necessary to the present case. The reflector R within the lamp box will stand behind the light. It would be to the left of the shield shown in Fig. 3 or at the right in Fig. 2 where the shield does not cover the light or lamp as will be clear. Said light is shown diagrammatically in Fig. 2 as a bulb supported by the bolt 4 and upstanding therefrom, and L' in Fig. 4 designates a bulb which is supported by the pivot bolt 6 at one side of the structure. Any suitable means for supporting this lamp L may be provided.

Mounted on the left hand pivot as shown in Fig. 4 is a finger 10 supporting the core 11 of a solenoid, which core is curved in an arc around said pivot; and the finger is rendered adjustable with respect to the arm 7 by any suitable means, such as a set screw 80 12 passing through the finger and bearing against the arm. By adjusting one element on the other and then tightening the set screw, the position of the core with respect to the arm may be changed at will. Mounted on the right hand pivot 6 in Fig. 4 is an extension 13 rendered adjustable with respect to the other arm 7 by any suitable means such as a set screw 14, and this extension is threaded as shown to receive a weight 15, a jam nut 16 being preferably employed to hold the weight when it is adjusted. The details just described are employed by preference, although of course they are not absolutely necessary. The core 95 might be carried by a finger fixedly connected with the arm, or it might be carried directly by the arm. The extension and weight might be omitted entirely if the shield and the remainder of the movable parts were not too heavy, but the weight is intended to be a counterbalance so that the raising of the shield as described below will not require too strong an electric current.

Carried by the left hand standard 5 in any suitable manner is a plate 20 which supports a curved solenoid broadly indicated by the numeral 21. As shown in Fig. 2, it is made up of a number of spools disposed in an arc, so that the core 11 may pass through them 110 as will be clear, and these spools are wound in a manner not necessary to show. The plate

and the solenoid may also be rendered adjustable in any suitable manner. As shown herein, the plate is triangular and is mounted on the pivot 6, but a bolt or rivet 22 passes 5 through the plate and the standard so that one is not adjustable with respect to the other. If the plate is made adjustable in any way, it may not be necessary to adjust the finger 10 with respect to the arm 7. 10 Much latitude must be allowed the manufacturer with respect to these details, and the proportions and materials of parts are not essential.

In operation, when the parts stand as 15 seen in Figs. 2 and 3 with the shield in what might be called a vertical plane, it completely covers the face of the reflector and lamp. If it be between the reflector and the light, as in Fig. 3, the shield in that case 20 does not of course cover the light; but if the parts be so disposed that the shield rests in front of the light and behind the glass or lens of the lantern, then the shield covers both the light and the reflector, and no beams 25 may shine in or shine out from the lamp in question. If the convex side of the shield is blackened, no beam which shines against the shield would be reflected. When now it is 30 desired to use the lamp in question a current is directed through the solenoid, and the core 11 is drawn into the same. This swings the arms 7 on their pivots 6 in a manner which will be clear, and the shield is caused to rise so that it stands in a horizontal plane above 35 the light and therefore out of the path of the light, whether shining direct or reflected from its own reflector. In other words, the shield is then at the top of the lamp box α inclosing the light L and its reflector R, and 40 wholly out of use. The arms 7 and standards 5, and the parts carried thereby being at opposite sides of the light, are of course out of the way. I have described this device as actuated electrically, but it is quite 45 within the spirit of the invention that it may be actuated mechanically, although means to this end are not set forth therein.

The foregoing description and the drawings have reference to what may be considered, the preferred or approved form 50 of my invention. It is to be understood that I may make such changes in construction and arrangement and combination of parts, materials, dimensions, et cetera, as 55 may prove expedient and fall within the scope of the appended claims.

Having thus fully described my invention, what I claim as new and desire to secure by Letters Patent, is:—

60 1. A dimmer for the purpose described, the same comprising a shield whose surfaces are non-reflective, arms projecting rigidly from the side edges of said shield, spaced standards, pivots connecting the arms and standards respectively, whereby the shield

may stand in an upright plane between the reflector and lamp or in a horizontal plane above its own pivots, and means for moving the shield to either position at will.

2. A dimmer for the purpose described, 70 the same comprising a shield whose surfaces are non-reflective, arms projecting rigidly from the side edges of said shield, spaced standards, pivots connecting the arms and standards respectively, whereby the shield 75 may stand in an upright plane forward of the reflector of a lamp or lantern or in a horizontal plane above its own pivots, a solenoid carried by one of said standards, and a core carried by one of said arms in 80 position to co-act with the solenoid, for the purpose set forth.

3. A dimmer for the purpose described, 85 the same comprising a shield whose surfaces are non-reflective, arms projecting rigidly from the side edges of said shield, spaced standards, pivots connecting the arms and standards respectively, whereby the shield may stand in an upright plane forward of the reflector of a lamp or lantern or in a 90 horizontal plane above its own pivots, a solenoid carried by one of said standards and comprising a series of spools disposed in an arc around the pivot to its standard, a finger adjustably mounted on the arm which 95 engages said pivot, and a core carried by said finger and curved to correspond with the curvature of the solenoid, for the purpose set forth.

4. In a shield of the type described, the 100 combination with a base, a pair of standards rising therefrom, a shield, arms projecting rigidly from the sides of said shield, and pivots between the respective arms and standards; of a solenoid mounted on one 105 standard and comprising a series of spools standing in an arc struck around the pivot of this standard, a finger movably mounted on said pivot, means for adjusting the position of the finger with respect to the arm 110 which is mounted on that pivot, and a curved core carried by the outer end of said finger and adapted to co-act with said solenoid, for the purpose set forth.

5. In a shield of the type described, the 115 combination with a base, a pair of standards rising therefrom, a shield, arms projecting rigidly from the sides of said shield, and pivots between the respective arms and standards; of means carried by one standard 120 and the arm pivoted thereto for swinging the shield as desired, an extension mounted on the pivot of the remaining arm, a weight adjustable on said extension, and means for adjusting the position of the extension with 125 respect to its arm.

6. In a shield of the type described, the combination with a base, means therein by which it may be pivotally mounted on a support, the base having a slot struck around 130

5 said pivotal means, and devices engaging said slot for holding the base in adjusted position; of a pair of standards rising from said base, a pair of arms pivoted to said standards respectively, a shield carried by the outer ends of said arms, and means for resting one edge of the shield on the base whereby said shield stands in an upright plane or swinging it around said pivots 10 whereby said shield stands in a horizontal plane above the base, for the purpose set forth.

7. In a shield of the type described, the combination with a base, means therein by 15 which it may be pivotally mounted on a support, the base having a slot struck around said pivotal means, and devices engaging said slot for holding the base in adjusted position; of a pair of standards rising from 20 said base, a pair of arms pivoted to said standards respectively, a shield carried by the outer ends of said arms, electrically controlled means connected with one standard

25 and the arm pivoted thereto for swinging the shield around said pivot, and an extension and counterbalance weight carried by the other arm, the whole for use substantially as hereinbefore described.

8. In a shield of the type described, the combination of a base, a pair of standards 30 carried by said base, a shield, arms projecting radially from the sides of said shield, and pivots between the respective arms and standards, of a finger movably mounted upon a pivot, means for adjusting the position of the finger with respect to the arm which is mounted on that pivot, and means for swinging said finger for moving said shield.

In testimony whereof I affix my signature 40 in presence of two witnesses.

CLARENCE E. STEVENS.
